BAG FILLING MACHINE

James C. Petrea, Durham, N. C., assignor to
 Wright Machinery Company, Durham, N. C., a
 corporation of North Carolina

Application August 1, 1951, Serial No. 239,661

16 Claims. (Cl. 226—55)

1

This invention relates to bag filling machines and particularly to an apparatus for supporting and positioning an opened bag while the same is being filled. The apparatus is particularly adapted for use with high speed weighing or measuring machines.

In general the apparatus comprising the preferred embodiment of the present invention consists of a fixed frame or standard having constantly rotating driving means and a rotatable turret. The turret carries radially extending arms each of which supports bag holding mechanism and material directing funnels. The drive arrangement is such that the turret is periodically indexed to present successive bag holding means to a filling station in response to completion of a weighing or other measuring operation performed by an associated machine. Intermediate drive means between the constantly rotating driving means and the turret are embodied in a friction clutch and a brake. The brake is applied by a cam fixed to the turret and arranged to stop the turret when a bag support reaches the filling station. Upon completion of the weighing or measuring operation and deposit of the material in a bag the brake is released to permit another indexing cycle of operation. The apparatus also includes novel means for agitating the bag as it is being filled and novel means for holding a bag and its contents on the apparatus and releasing the same at a predetermined station.

It is therefore an object of this invention to provide an improved bag filling machine capable of high speed operation.

Another object of the invention is to provide a bag filling machine of the nature indicated which is simple in construction and economical to manufacture.

It is a further object of this invention to provide novel indexing means in a bag filling apparatus permitting unusually high operating speeds.

Another object of this invention is to provide novel means for locking a bag to the apparatus and for spreading the same to insure proper delivery of material thereto.

Another object of the invention is to provide a bag filling machine having bag supports arranged circumferentially on a rotatable turret and adjustment means for circumferentially adjusting the bag holding means individually.

A still further object of this invention is to provide, in a bag filling machine, an element for frictionally retaining an empty bag on the apparatus and for thereafter positively clamping the bag to its support.

2

Another object of the invention resides in means to prevent swinging of a filled or partially filled bag out of its intended path of travel.

Another object of the invention resides in the provision of automatically operable means to insure delivery to a bag of material deposited in a funnel.

A further object of the invention is to provide a bag filling machine readily adaptable for use with any high speed material weighing or measuring apparatus.

Other objects and advantages will appear to those skilled in the art as the description proceeds in connection with the accompanying drawings illustrating a preferred embodiment of the invention.

In the drawings:

Figure 1 is a side elevational view of a preferred form of bag filling machine constructed in accordance with the present invention.

Figure 2 is a top plan view of the embodiment of Figure 1 with the cover plate removed.

Figure 3 is a vertical sectional view of the apparatus taken substantially along the line 3—3 of Figure 2.

Figure 4 is a view similar to Figure 1 but with portions thereof broken away and other portions shown in section. The view of Figure 4 is taken from a position substantially at "station 2" as seen in Figure 2.

Figure 5 is a fragmentary sectional view through the star wheel agitator mounted on the cover plate.

Figure 6 is a fragmentary sectional view taken substantially along the line 6—6 shown in Figures 3 and 4.

Figure 7 is a detail sectional view taken along the line 7—7 of Figure 6.

Figure 8 is a sectional view taken along the line 8—8 of Figure 6.

Figure 9 is a sectional detail taken along the line 9—9 of Figure 6, and

Figure 10 is a detailed sectional view similar to the right-hand portion of Figure 3 but showing the relationship of the parts at a different station from that shown in Figure 3.

Referring first to Figure 1 of the drawings, a base member 2 fixedly supports an upstanding column or post 4 on which the mechanism of the present invention is supported. The post 4 also adjustably supports a rack or holder 6 for a stack of empty bags.

Referring next to Figure 3, the post 4 is shown as being provided with a frame plate or support 8 having a hub surrounding the post and

which may be fixed thereon in any suitable manner such as by set screws or the like (Fig. 4). The support plate 8 is provided with suitable brackets or bosses to which a motor 10 is attached. The motor 10 may be a gear type motor having an out-put shaft extending upwardly through the support 8 and carrying a pinion 12 keyed to its upper end. The axis of the pinion 12 is offset laterally relative to the post 4 and the pinion meshes with a rotatable gear 14 journalled on the post 4. The gear 14 is provided with an elongated upstanding hub 16 and a lower surface 18 bearing upon the upper surface of support plate 8. The surface 18 constitutes a thrust bearing for the gear 14. To the upper surface of the gear 14 an agitator plate 20 is secured by means of screws 22. Surrounding the hub 16 of the gear 14 above the agitator plate 20 is a carrier plate 24 mounted for rotation about the hub 16 of gear 14 and supported by the upper surface of agitator plate 20. The carrier plate 24 has a hollow cylindrical drum 26 fixed to its upper surface by means of screws 28 and the plate 24 and drum 26 are thus arranged to rotate about hub 16 as a single unit. The drum 26 is provided with an outwardly extending flange 30 substantially mid-way of its height, which flange constitutes a cam to be described later. The upper surface of the carrier 24 adjacent the hub 16 and within the drum 26 defines a friction surface engaging a friction driving ring 32. The driving ring 32 is keyed to the hub 16 of gear 14 as at 34 to be driven thereby but is free to move axially on the hub. A pressure ring 36 is also keyed to the hub 16 above driving ring 32 and is held in axial position thereon by an adjustable backing ring 38 threaded to the outer surface of the hub 16. The driving ring 32 and pressure ring 36 are provided with opposed recesses or openings into which the ends of compression springs 40 extend. The compression springs 40 hold driving ring 32 in snug frictional engagement with the upper surface of the carrier 24 to effect a frictional drive thereto from the hub of gear 14. The ring 38 may be adjusted axially of the hub 16 to thereby regulate the pressure applied to the friction drive described and for this purpose the ring 38 is provided with holes 39 for engagement by a suitable spanner wrench or the like.

The cylindrical drum 26, above the cam flange 30, is provided with a smooth cylindrical outer surface constituting a brake drum, to be described later.

Referring now to Figure 2 along with Figure 3, the plate 24 carries a plurality of radially extending arms 42 having forked outer ends and fairly wide inner end portions. The inner end portions of the arms 42 are provided with radially extending adjustable eye-bolts 44. The eye-bolts of each arm are circumferentially spaced and held in radially adjusted position in the arms 42 by means of suitable lock nuts 46. Each eye-bolt engages a suitable spherical bearing 48 mounted on carrier plate 24 by a bolt 50. Thus each arm 42 is mounted on the carrier plate 24 and by suitably adjusting the eye-bolts 44 in arms 42 the circumferential position of the outer ends of the arms 42 may be adjusted in relationship to each other. The spherical bearings 48 provide for pivotal movement of the arms 42 in a vertical direction relative to the carrier 24. The forked outer end portions of arms 42 engage and are attached to

suitable brackets or ears 52 on opposite sides of material directing funnels 54. The funnels 54 are for the purpose of directing measured or weighed material into bags carried by the arms 42 and held thereon by mechanisms to be described later.

In operation the bag filling machine disclosed herein is to be used in conjunction with weighing or similar mechanism adjacent to which it is located. The weighing or measuring mechanism preferably includes a delivery chute located at a fixed position and defining a filling station. It is necessary therefore that the carrier 24 be periodically indexed to position successive funnels 54 at the filling station. To accomplish this indexing function the mechanism of Figures 6 through 9 is provided.

As previously indicated, the gear 14 is constantly driven by motor 10 and the hub 16 and friction clutch 32-36 mounted on the gear 14 are effective to establish a friction drive to the carrier 24. As previously stated, the upper portion of cylinder 26 defines a brake drum and a suitable brake lining 56 (see Fig. 6) extends around the brake drum 26. One end of the brake lining 56 is fixedly supported relative to the post 4 by means of a pin 58 (see also Fig. 9) extending through an end bracket 60 on the brake band 62 of brake lining 56. The anchor pin 58 extends upwardly through an elongated slot 64 in a supporting bracket 66 fixedly clamped to the post 4 above the hub 16. The bracket or support 66 is shown by dotted lines in Figure 6 and in full lines in Figures 2 and 3 of the drawings. The anchor pin 58 is threaded at its upper end and is provided with a fixed collar 68 below the support 66. A nut 70 threaded to the upper end of the anchor pin 58 is effective to lock the pin in any selected position longitudinally of the slot 64 which extends generally tangentially of brake drum 26. An adjusting screw 72 extends through the side wall of the support 66 into and longitudinally of slot 64 and into engagement with a side of the anchor pin 58. Adjustment of screw 72 will effect adjustment of anchor pin 58 in slot 64 when nut 70 is loosened and thereafter the nut 70 may be tightened to lock the pin 58 in position and a lock nut 74 turned to lock adjusting screw 72, thus fixing the anchor pin 58 in selected position.

The other end of the brake band 62 of the brake lining is provided with a bracket 76 formed with a pair of ears 78 having aligned openings therethrough. A pin 80 extends through the aligned openings of the ears 78 and through one end of a lever 82. The lever 82 is freely pivoted on a pin 84 carried by support 66. The pin 84 defines a fixed axis about which lever 82 is free to pivot. The downwardly extending portion of pin 84 below support 66 is of greater length than the thickness of lever 82. A cam follower lever 86 is provided with a forked end portion (Fig. 7) embracing the pivoted portion of lever 82 and provided with aligned openings through which pin 84 passes. The pin 84 thus pivotally supports both the lever 82 and the cam follower lever 86 for independent pivotal movement about the same fixed axis.

As previously indicated the cylindrical drum 26 is provided with an integral flange 30 having an outer peripheral edge constituting a cam. The general configuration of the cam is shown to best advantage in Figure 2 and is provided with a series of outwardly projecting lobes, there being

one lobe for each of the arms 42 of the apparatus. The plane in which the cam 30 lies extends below the cam follower lever 86. A cam following roller 88 is rotatably carried by a pin 90 supported at the outer end of cam follower lever 86 and is positioned therebelow at a level corresponding to the plane of the cam 30 and in position to engage the outer periphery of the cam. A suitable pressure fitting 91, of conventional construction, is carried by pin 90 to facilitate lubrication of roller 88 in a well-known manner.

As best seen in Figure 6 the lever 82 extends radially outwardly beyond pin 84 and carries a pivot pin 92 at its outer end. Pivoted supported on the pin 92 is a pawl 94 held thereon by collar 95 and extending transversely of the lever 82. One end of the pawl 94 is shaped complementary to a notch 96 in the outer edge of cam follower lever 86 and the other end of the pawl 94 extends to the other side of pivot pin 92 and is pivoted to a link 98, as at 99, which link is pivoted, at 100, to the armature 102 of a solenoid 103. The solenoid 103 is supported by the support member 66 clamped to post 4. A tension spring 104 (see Figures 2 and 4) is connected at one end to a post 106 fixed to the support 66 and at its other end to the armature 102 of the solenoid 103 to thereby urge the armature to the left as seen in Figure 6 and to rock pawl 94 in a clockwise direction about pivot pin 92 to position the upper end of the pawl in the notch 96 of cam follower lever 86.

With the parts in the position thus described and with the cam following roller 88 at a low point of cam 30, the brake band 62 is "released" and the cylinder 26 and carrier 24 are free to be rotated by the friction clutch 32. As the drum 26 and cam 30 rotate with carrier 24 the cam 30 will be rotated past the roller 88 and a lobe of the cam will force roller 88 radially outwardly and pivot cam follower lever 86 about the axis of pin 84. Since spring 104 is, at this time, holding pawl 94 in the notch 96, pivotal movement of the follower lever 86 outwardly will result in the pawl 94 being put under compression and thus applying a torque to lever 82 in such direction as to tighten the brake band 56 about the brake drum 26. The radial dimensions of the cam lobes are such that sufficient braking pressure will be applied to the drum 26 at the time the roller 88 approaches the crest of a cam lobe to overcome the torque applied by the friction clutch and effect stopping of the carrier 24.

The support 66 may also be provided with a downwardly extending finger or bracket 108 through which a stop screw 110 is threaded in position to engage lever 82 and act as a stop therefore to limit the extent of releasing movement of brake lining 56. The brake band 62 is sufficiently resilient to provide the necessary releasing bias to brake lining 56.

After operation of the brake band in the manner described to stop the carrier 24 at an indexed position, the lobe of the cam 30 will maintain the brake band in "set" condition and hold the carrier stationary until the brake is released by some external influence. Upon application of a suitable energizing current to the solenoid 103 the armature 102 thereof is drawn to the right as seen in Figure 6 in opposition to the bias of spring 104, thus swinging the pawl 94 counter-clockwise about its pivot pin 92 and withdrawing the upper end thereof from the notch 96. With the pawl 94 withdrawn from notch 96 the brake band is no longer maintained under tension and is thereby

released to permit another cycle of indexing operation of the carrier through the influence of the friction clutch. It is to be understood that an impulse of current is applied to the solenoid 5 103 in response to completion of a weighing or measuring cycle in a machine or apparatus supplying measured or weighed quantities of material to the bag filling machine of this invention. The impulse applied to the solenoid 103 is only momentary so that upon release of the brake and commencement of an indexing cycle the armature 102 is again released to the action of spring 104 and the end of the pawl may again enter notch 96 to effect setting of the brake and stopping of the carrier when the roller 88 approaches the crest of the next cam lobe. By the mechanism thus far described it will be seen that a carrier such as the carrier 24 may be periodically indexed to position successive hoppers at a given station and that such sequential indexing cycles may be performed at a relatively high rate of speed. The braking arrangement is susceptible to high speed operation since the only masses necessary to accelerate are those carried by the carrier itself. The driving mechanism rotates constantly and it is unnecessary to expend power in accelerating and stopping the driving mechanism at each indexing cycle, while the friction clutch and brake insure smooth operation and maximum rates of acceleration of the carrier. The cam means for setting the brake produces a definite and positive indexing at a predetermined station within very close limits and the solenoid 20 release for the brake provides an instantaneous response to abruptly release the brake and effect indexing movement in the least possible time.

The funnels 54 carried by the outermost ends of arms 42 are provided with downwardly extending chutes 112 riveted or otherwise fixed thereto. The chutes 112 are generally U-shaped in horizontal section. The bottoms of the chutes, that is, the inner or closed sides extend downwardly and outwardly at a substantial angle to the vertical as clearly apparent from the drawings.

45 Each of the arms 42 has a downwardly extending leg portion 114 outwardly of the outer periphery of support plate 8 and closely adjacent the forked end thereof near funnel 54. The legs 114 are preferably formed integrally with the arms 42 and terminate at their lower ends in laterally spaced fingers or brackets 116 (most clearly seen in Fig. 1). The fingers or brackets 116 may in fact extend upwardly in spaced relation to the arms 42 and be joined at their outer edges 50 by a transverse web. The brackets 116 are provided with aligned openings at their lowermost ends in which a rock shaft 118 is journalled. Fixed to the shaft 118 between brackets 116 is a unitary U-shaped structure comprising a bottom plate 120 and spaced ears 122. The ears 122 are fixed to the shaft 118 in any suitable manner adjacent the inner faces of brackets 116. Rigidly fixed to the bottom plate 120 is a downwardly extending follower arm 124 arranged to extend at 55 an angle from the lower surface of the plate 120, all as clearly shown in Figure 3 of the drawings. The follower arm 124 has a cam following roller 126 journalled on the lower end thereof. A stud 128, fixed to the follower arm 124 extends inwardly therefrom and is provided with an eyelet at its inner end. A tension spring 130 is attached at one end to the eyelet on stud 128 and is attached at its other end to a suitable fitting 132 on the inner side of the web joining brackets 60 116. It will be readily apparent that the spring

130 will be effective to urge follower arm 124 and its associated U-shaped bracket clockwise about the axis of shaft 118 as viewed at the right side of Figure 3.

Between the ears 122 of the U-shaped bracket a clamp member 134 is mounted on shaft 118 for limited rotation thereon. The clamp member 134 extends to opposite sides of the shaft 118 and is provided with a bottom surface that may be spaced parallel to but spaced from the upper or inner surface of the plate 120. Inwardly of the shaft 118 the plate 120 and clamping member 134 are provided with opposed recesses receiving the ends of a compression spring 136. The compression spring urges the clamp member 134 to rotate clockwise relative to plate 120, as seen in Figure 10, but the upper surface of plate 120 at the outer edge thereof constitutes an abutment to be engaged by a portion of the flat surface on the bottom of clamp member 134 to limit relative rotation in that direction.

The shaft 118 extends beyond one of the brackets 116 and has a crank arm 138 fixed thereto (Figs. 1 and 4). The crank arm 138 extends upwardly from the shaft 118 to a level slightly below the bottom of the funnel 54. A cross link 140 is pivoted at one end to the upper end of crank arm 138 and extends outwardly therefrom to a position adjacent the outer edge of the upper portion of the chute 112. The funnel 54 has integrally formed thereon at opposite sides of the outer face thereof a pair of ears or brackets 142 in which a rock shaft 144 is journaled. The rock shaft 144 extends outwardly beyond one of the ears 142 and has a downwardly extending crank arm 146 fixed thereon. The cross link 140, previously described, is pivoted at its outer end to the lowermost portion of the crank arm 146. Fixed to the shaft 144 between the ears 142 is a spreader mechanism 148 comprising angularly related portions 150 and 152 (see Fig. 3). The portion 152 comprises a relatively narrow finger extending downwardly practically within the chute 112 when the follower arm 124 is swung outwardly to the limit of its travel, as shown in Figure 3. Preferably the crank 146 is angularly adjustable on shaft 144 and link 140 is so constructed as to be adjustable in length, all to provide for establishing the proper relationship between the parts described.

The support plate 8 supports downwardly extending posts 154 to the lower ends of which a cam track 156 is fixed. The cam track 156 extends arcuately about the post 4, generally concentric thereto and is provided with an outer surface defining a cam track for the roller 126. The cam track 156 extends only a portion of the way around the apparatus, extending through three stations of the machine (see Fig. 2). One end portion of the track 156 is provided with an outwardly projecting lobe 158 whereas the remainder of the track surface extends concentrically about the post 4 at a uniform distance therefrom but inwardly of the outer portion of lobe 158. While the roller 126 is at or near the crest of cam track lobe 158 the shaft 118 is rotated counter-clockwise to such an extent that the upper surface of plate 120 engages clamp member 134 and rotates the same counter-clockwise sufficiently far to remove the upper end thereof from contact with the outer surface of chute 112. At the same time, the crank arm 138 acting through link 140 and crank 146 retracts the spreader 150-152 to the position shown at the right of Figure 3. In this position

the parts are in position to release a filled bag from the apparatus.

When the roller 126 is in engagement with the concentric portion of cam track 156 the parts are in the relative position indicated in Figure 10 of the drawings, that is, the arm 124 is held at such an angle that the upper surface of plate 120 is withdrawn from that portion of clamp member 134 to the right of shaft 118 to permit the clamp member to swing clockwise to position its free end against the outer surface of chute 112. The parts are so proportioned that the end of member 134 engages chute 112 while the opposite end thereof remains spaced from the upper surface of plate 120. The compression spring 136 is effective at this time to yieldably hold clamp member 134 against the side of chute 112. With the parts in this position an empty bag may be slipped upwardly over the chute 112, which later enters the open mouth of the bag. The bag may be moved upwardly to the position indicated by dotted line at the left side of Figure 4. As will be apparent from the drawings one wall of the bag will be positioned between the clamp member 134 and the surface of the chute 112. The bag is intended to be manually placed on the apparatus in the manner described while the parts are in the relative positions indicated in Figure 10. Thus, the clamp member 134 may be resiliently retracted from contact with chute 112 by the mere act of passing one wall of the bag therebetween and compression spring 136 thereupon acts to yieldably press the bag against the chute and frictionally hold it in the position described. During the positioning of the bag on the chute the bag spreader elements 150-152 will be in substantially the position shown at the right of Figure 3. Upon movement of the carrier and bag supporting mechanism to a station beyond the end of cam track 156 opposite the end having lobe 158 tension spring 130 becomes effective to swing follower arm 124 inwardly toward post 4 and thus move the plate 120 relative to clamp member 134 until the portions thereof adjacent the spring 136 come into actual engagement. The spring 130 then applies torque directly to the clamp member 134 and effects firm locking of member 134 against the chute 112 with sufficient pressure to support a bag and its contents. At the same time the arm 124 moves inwardly under the influence of spring 130, the crank arm 138, link 140, crank 146 and shaft 144 will be actuated to move the bag spreader outwardly to the position shown at the left side of Figure 4. When retracted to the position shown at the right of Figure 3, the spreader finger 152 is in such position that the upper edge of a bag placed on the chute 112 extends upwardly above the lower end thereof. Upon movement of the finger 152 to the position shown at the left of Figure 4 the mouth of the bag is spread sufficiently to receive all material deposited in funnel 54 and passing therethrough.

As previously described a vibrator plate 20 (Fig. 3) is fixed to the upper surface of the main drive gear 14 so that the vibrator plate is rotated constantly with the driving mechanism. The plate 20 extends radially outwardly to a position adjacent the downwardly extending legs 114 and is provided with a vertical circumferential flange 160. The flange 160 provides reinforcement for the outer edge of the plate 20 and extends upwardly thereabove. The upper surface of the flange 160 is formed with a vertically undulating or wavy upper surface 162. The arms

42, at a location near the upper ends of the legs 114 are each provided with an inwardly extending trunnion pin 164 on which a roller 166 is rotatably mounted. The roller is in position to engage and ride upon the undulating surface 162 of the vibrator plate 20. As clearly evident from Figure 3 of the drawings the roller 166 is of an axial length substantially greater than the radial dimension of the surface 162 whereby it extends radially outwardly beyond that surface. As previously described, the arms 42 are pivotally mounted to the carrier plate 24 for vertical movement in a plane radial to the post 4. The rollers 166 riding upon the surface 162 constitute a vertical support for the arms 42. The support plate 8, fixed to post 4, extends outwardly below the vibrator plate 20 and a slight distance radially outwardly thereof. A portion of the periphery of support 8 is provided with an upstanding flange 168 terminating at its upper edge in a smooth horizontal track surface slightly above the highest portions of the undulating surface 162 and is concentric thereto. It will be apparent that, since vibrator plate 20 rotates constantly, vertical vibratory movements will be imparted to the arms 42 during periods when the carrier plate 24 and its associated arms 42 are being held stationary by the braking mechanism. That is, vibratory movements are imparted to the arms and elements carried thereby when they are stationary at stations across which the flange 168 of support 8 does not extend.

The support 8 also carries downwardly extending posts 170 to the lower end of which brackets 172 are attached by means of cap screws 174. The brackets 172 are provided with downwardly extending portions 176 to which clamp blocks 178 are attached for vertical adjustment along the portions 176. The portions 176 extend downwardly and outwardly substantially parallel to the bottom or closed sides of the chutes 112. The clamp blocks 178 are each provided with an outwardly facing groove 180 receiving a resilient bent rail member 182. A portion of the rail 182 extends concentrically about the post 4 in position to engage the bottom portion of a bag, below the chute 112, as indicated at the left side of Figure 4. Since the bags are clamped to the chute at a single point on the inner side thereof, it will be apparent that the weight of material deposited in the bag will tend to cause the bag to swing inwardly about its clamped point as a fulcrum. The bag rail 182 is provided for the purpose of preventing such inward swinging movement of the bag. As shown in Figure 2 the bag rail 182 extends only part way around the apparatus and its end portions are directed inwardly to effect gradual engagement with the bag and to disengage the bag prior to its release from the apparatus. The rail 182 is resilient since adjustment thereof along portions 176 of brackets 172, to cooperate with bags of different length, results in a change of radius of curvature of the rail.

As shown in Figures 1, 3 and 4 the post 4 supports a cover plate 184 at its upper end. The cover plate may be attached to a ring 186 frictionally received over the upper terminus of post 4 to be fixedly held thereby. The cover plate 184 is preferably of segmental spherical shape and extends outwardly and downwardly to a position closely adjacent the inner edges of funnels 54 to thereby enclose and protect the drive and indexing mechanism of the apparatus and

to act as a safety guard for many of the moving parts.

At a position adjacent one of the stations to which the funnels 54 are indexed, the cover plate 184 is formed with an integral boss 188 to which a bracket 190 is attached. The bracket 190 supports a horizontally extending plate 190 of a shape in horizontal plane substantially the same as the shape of the mouth of a funnel 54. The plate 190 is supported in a position just slightly above the tops of funnels 54 so that a funnel therebeneath is substantially closed by the plate. The bracket 190 also supports a suitable blower 192 having a discharge duct 194 directed downwardly through an opening 196 in plate 190 to thereby direct a blast of air downwardly through the funnel 54 therebeneath. It is intended that the blower 192 be supported at a station immediately following that at which a bag is first locked to the chute 112 so that the downwardly directed blast of air will enter the bag and completely open the same to material receiving position at about the time the bag first engages rail 182.

At another station of the apparatus, preferably at station 6, the cover plate 184 is provided with a further integral boss 198 (see Fig. 5) which in turn supports a bracket 200 to which an upwardly and outwardly extending shaft 202 is fixed. A collar 204 is fixed to the shaft 202, such as by means of a set screw, and constitutes a bearing surface for a star wheel agitator 206. The star wheel agitator 206 is provided with a hub 208 journaled on the shaft 202 and a compression spring 210 reacting against a second collar 212 on shaft 202 holds the hub 208 firmly against collar 204 to thereby provide a friction brake to prevent free spinning rotation of the wheel 206. As best seen in Figure 4, the wheel 206 comprises a plurality of radially extending spaced arms fixed to the hub 208. The axis about which the wheel 206 rotates, as defined by shaft 202, is such that the ends of the legs of the star wheel project into the funnels 54 a substantial distance and the paths of movement of the arms and the funnels are generally the same throughout a minor portion of each. As the carrier 24 and funnels 54 are periodically indexed to successive stations the sides of the funnels 54 engage the sides of the star wheel legs and cause rotation thereof much in the nature of a pair of gears. The legs are arranged to project into the mouth of the funnels to insure movement of material deposited therein through the chutes 112 into the bags supported thereby. The star wheel agitator is shown in the drawings at station 7 merely for convenience of illustration, it being preferably located at station 6.

Referring now particularly to Figure 2 of the drawings it will be noted that the apparatus consists of eight arms 42 and eight associated funnels 54. Likewise the cam 30 is provided with eight equally spaced lobes for effecting setting of the braking mechanism. Thus there are eight stations at which each funnel is successively brought to rest. For convenience of description the drawings include legends indicating corresponding stations in the different views. As shown in Figure 2 the cam track 156 for operating the bag clamping and spreading mechanisms extends from station 8 through station 2 and terminates short of station 3. The high lobe of the cam track 156 is located at station 8 and it will be noted that the bag supporting rail 182 ends at station 8 with its end portion located substantially inwardly of the rest of the bag sup-

11

porting rail. At station 8 the parts are moved to the position shown at the right side of Figures 3 and 4 whereupon a filled bag is released at that station and dropped onto a take-away conveyor (not shown).

During indexing of a funnel and its associated mechanism from station 8 to station 1 (in a clockwise direction as viewed in Fig. 2) the bag gripping means and cam track follower assume the relative positions shown in Figure 10. An operator takes a position adjacent stations 1 and/or 2 and manually applies empty bags to the chute 112 at either station 1 or 2. The empty bag supply rack 6 may be vertically and angularly adjusted on the post 4 to position the supply of empty bags at a location convenient to the operator. In actual use the bag holder 6 is positioned somewhere between stations 1 and 2, as shown in Figure 2. For convenience of illustration, the bag holder 6 is shown in Figures 1 and 4 at a position below station 8 but clearly that cannot be its operational position since that space is to be occupied by the take-away conveyor referred to above. As stated above empty bags are manually taken from the rack 6 and placed on the chutes 112 in the manner described while the latter are at either station 1 or 2. A bag thus positioned on the apparatus is yieldably held thereon with the parts acting as described in connection with Figure 10. Subsequent indexing of the bag to station 3 results in the roller 126 passing completely off the tapered end of cam track 156 with the described resulting positive clamping of the bag to the chute and operation of the spreader fingers 152 to open the mouth of the bag prior to arrival at station 3. The blower 192 is shown at station 4 merely for convenience of illustration. It is preferred that in actual practice the blower be positioned over station 3 to completely expand the bag at that station and just before the same engages bag supporting rail 182.

As also shown in Figure 2 of the drawings the upstanding flange 168 of support plate 8 extends concentrically around the apparatus from a starting position ahead of station 8 to a terminal position slightly ahead of station 4. Thus, the funnels and bag supporting mechanisms at stations 1, 2 and 3 are supported by the smooth track at the upper edge of flange 168 and at a level above the undulating surface 162 of vibrator plate 20. Thus the arms and funnels at stations 1, 2 and 3 are not vibrated as the plate 20 rotates beneath them.

As an empty but clamped and opened bag is moved from station 3 to station 4 it engages bag rail 182 and during that indexing movement the roller 166 associated therewith passes off the flange 168 and the bag supporting means is then supported solely by the undulating surface of vibrator plate 20. Station 4 is preferably the filling station of the apparatus. The machine described herein is intended to be used in series with a suitable material weighing or measuring apparatus. The weighing or measuring apparatus will be provided with suitable discharge means for directing charges of material to a position immediately above the funnel 54 at station 4. During the filling operation the funnels are stationary and the funnel at station 4, being supported by vibrator plate 20, which rotates constantly, is caused to vibrate in a vertical direction at a relatively high frequency to thereby compact material deposited in the bag. During indexing movement of the filled bag from

12

station 4 to station 5 the arms 42 and plate 20 move in unison, therefore no vibratory motion is imparted to the bag support during actual indexing movement between stations. As the filled bags come to rest at stations 5 and 6 they are again vibrated to insure compacting of the material therein.

As the filled bags pass through station No. 6 one leg of the star wheel agitator 206 enters the funnel at that station to insure discharge of any material that may have compacted and "bridged" itself across the throat of the funnel. As the filled bag moves from station 7 to station 8 the bag supporting rail 182 recedes inwardly away therefrom while the clamping means are released by the lobe 158 of cam track 156 and the bag is thus dropped to the aforementioned conveyor for removal.

Preferably the weighing or measuring apparatus provides the electrical impulse applied to solenoid 103 whereby to release the turret 24 for indexing in synchronism with delivery of material from the weighing mechanism to the bag filling apparatus described herein. However, any other suitable means may be employed to provide the required impulse at the proper time.

While a single preferred embodiment of the apparatus has been shown and described it is to be understood that many modifications may be resorted to within the scope of the invention and many subcombinations may be substituted as equivalents without departing from the scope of the invention as defined by the appended claims.

I claim:

1. In a bag filling machine, a constantly rotating member, a carrier mounted for rotation about the same axis as said member, means for intermittently connecting said carrier and said member for rotation together as a unit, bag holding means movably mounted on said carrier, said member having means thereon cooperating with said bag holding means and operable in response to relative rotation between said member and carrier to vibrate said bag holding means when said member rotates relative to said carrier and whereby no vibration is imparted to said bag holding means when said carrier is connected to said member.

2. A machine as defined in claim 1 wherein said means for intermittently rotating said carrier comprises indexing means for stopping said bag holding means at a plurality of stations, and means at certain of said stations for preventing engagement of said bag holding means by said means carried by said member whereby to prevent vibration of said bag holding means when stationary at said certain stations.

3. In a bag filling machine, a stationary frame, rotary driving means mounted on a fixed axis on said frame, means for imparting constant rotation to said driving means, a carrier rotatably mounted on said frame coaxial to said driving means, a bag holding means mounted on said carrier for limited movement relative thereto in a radial plane, means connecting said driving means to said carrier to index said bag holding means to successive predetermined stations, a vibrator fixed to said driving means and having an undulating surface thereon, said surface engaging a portion of said bag holding means at certain of said stations to thereby vibrate the latter in said radial plane during periods when said carrier is stationary.

4. A machine as defined in claim 3 including

fixed track means at other than said certain of said stations, said track means, being engageable with a portion of said bag holding means to hold the latter free of said undulating surface whereby said bag holding means is not vibrated when stationary at said other stations.

5. In a bag filling machine, a stationary frame, rotary driving means mounted on a fixed vertical axis on said frame, means for imparting constant rotation to said driving means, a carrier rotatably mounted on said frame above and coaxial to said driving means, a radially extending bag holding arm pivoted to said carrier for movement relative thereto in a vertical plane, means for intermittently driving said carrier from said driving means and at the same speed to thereby index said arm to successive predetermined stations, a member fixed to said driving means and having an annular portion provided with an upper vertically undulating surface below a portion of said bag holding arm, a roller on said arm normally urged to rest on said surface whereby said arm may be vertically supported by said member and whereby said arm may be vertically vibrated when said carrier is stationary with said arm at certain of said stations but not vibrated when said carrier and arm are moving between said stations in unison with said member.

6. A machine as defined in claim 5 wherein a portion of said roller extends radially outwardly of said undulating surface, a fixed arcuate track on said frame outwardly of said member and in the path of said extending portion of said roller, said track having a smooth upper surface higher than said undulating surface and extending through certain of said stations whereby said track supports said roller and arm free of said undulating surface at said certain stations.

7. A machine comprising, a carrier having bag supporting means thereon, said bag supporting means comprising a downwardly extending element having a surface engageable with an inner face of one wall of a bag, a clamp element on said carrier and yieldable means urging said clamp element toward said surface to thereby frictionally hold a bag between said element and surface, and locking means actuatable to positively lock said clamp element firmly against said surface to thereby lock a bag and its contents to said carrier, said clamp element comprising a bar pivoted on said carrier adjacent said surface and having one end thereof directed generally upwardly to pivot into engagement with said surface.

8. A machine as defined in claim 7 wherein said clamp element is spring-pressed toward said surface and wherein said locking means comprises a clamp actuator, movable on said carrier by spring means, in a direction to engage and positively press said clamp element against said surface, and cam means to move the same away from said clamp element.

9. A machine as defined in claim 8 including an abutment on said clamp actuator engageable with said clamp element after movement of said actuator a predetermined distance away from said element, a portion of said cam being so dimensioned as to move said actuator more than said predetermined distance and thereby overcome said yieldable means and release a bag held by said clamp element.

10. In a bag handling machine, a carrier having bag supporting means thereon, means for intermittently moving said carrier to position said bag supporting means at successive predetermined

stations, said bag supporting means comprising a downwardly extending element having a surface engageable with an inner face of one wall of an empty bag, a clamp element pivoted to said carrier on an axis fixed thereon, an end of said clamp element being swingable into engagement with said surface to frictionally grip the wall of said bag therebetween, said clamp element having portions on opposite sides of said axis, a clamp actuator mounted for pivotal movement about said axis, said clamp actuator having abutments on opposite sides of said axis, said abutments being opposed to and spaced from the said portions of said clamp elements, first spring means between one of said abutments and its opposed portion and urging said clamp element in such direction as to press said end thereof against said surface, further spring means biasing said clamp actuator to engage said one of said abutments and its opposed portion to lock said end of said clamp element against said surface, and a cam track at and between certain of said stations to engage said clamp actuator and pivot the same in opposition to said further spring means sufficiently far to release said clamp element to the action of said first spring means.

11. A machine as defined in claim 10 wherein a portion of said cam track at one of said stations is so dimensioned as to swing said clamp actuator sufficiently to engage the other of said abutments with its opposed portion and positively swing said end of said clamp element away from said surface to release a bag held thereby.

12. In a bag filling machine, a carrier having bag supporting means thereon, means for intermittently moving said carrier to position said bag supporting means at successive predetermined stations, said bag supporting means comprising a downwardly extending chute of generally U-shaped in horizontal section and adapted to extend into the mouth of a bag, yieldable means for frictionally holding a bag wall against the closed side of said chute, a bag expander pivoted to said carrier and arranged to swing to a position within said chute or to swing outwardly through the open side thereof to expand a bag thereon, and means operable at and between certain of said stations to swing and hold said expander outwardly.

13. In a bag filling machine, a carrier having bag supporting means thereon, means for intermittently moving said carrier to position said bag supporting means at successive predetermined stations, said bag supporting means comprising a downwardly extending chute of generally U-shape in horizontal section and adapted to extend into the mouth of a bag, yieldable means for frictionally holding a bag wall against the closed side of said chute, a bag expander pivoted to said carrier and arranged to swing to a position within said chute or to swing outwardly through the open side thereof to expand a bag thereon, a movable cam follower on said carrier arranged to simultaneously lock said yieldable means against said chute and swing said bag expander outwardly, when moved in one direction, spring means urging said cam follower in said one direction and a fixed cam track at and between certain of said stations arranged to engage said cam follower and move it in the other direction.

14. In a bag filling machine, a carrier having bag supporting means thereon, means for intermittently moving said carrier to position said bag supporting means at successive predetermined stations, said bag supporting means comprising

15

gripping means for holding only one side wall of a bag adjacent the top thereof, the other side of said bag being unsupported, a stationary guide rail extending in the direction of movement of said carrier, said rail being positioned to slidably engage the said side wall of the bag adjacent the bottom thereof to prevent lateral swinging movement of said bag about said gripping means.

15. In a bag filling machine, an upstanding fixed post, a carrier mounted for rotation about said post, means for intermittently indexing said carrier about said post, said carrier having a plurality of spaced material receiving funnels around the periphery thereof, means for supporting a bag on said carrier below each of said funnels, said post extending above said carrier and having a cover member fixed to the top thereof and extending outwardly to a position adjacent said funnels, a rotary structure carried by said cover on an axis oblique to said post and having a plu- 20

5 rality of radial arms, the ends of adjacent arms being so spaced as to be successively receivable in adjacent funnels as said carrier moves about said post, to insure movement of material through said funnels, said rotary structure being rotated by movement of said funnels in engagement with said arms.

16. A machine as defined in claim 15 including friction brake means for said rotary structure to retard free spinning rotation thereof.
